UNITED STATES PATENT OFFICE.

WALTER C. GAGE, OF HOLYOKE, MASSACHUSETTS, ASSIGNOR TO WORTHINGTON PUMP AND MACHINERY CORPORATION, OF NEW YORK, N. Y., A CORPORATION OF VIRGINIA.

PUMP PISTON.

Application filed June 22, 1926. Serial No. 117,672.

This invention relates to pistons and more particularly to pistons designed for use in displacement pumps employed for pumping hot liquid, such as hot petroleum or its products, especially pumps used in oil refining operation, such as cracking stills for producing gasoline.

In pumps commercially known as hot oil pumps considerable difficulty, loss of time in operation with reduced refinery capacity and consequent expense is encountered in that the wear of the piston and the pump cylinder lining is very rapid so that on certain installations it has been necessary to replace pump pistons every few months, and also due to the fact that the snap rings stick and become practically integral parts of the piston, due to carbon or other accumulations, thereby destroying their effectiveness and making it necessary to cut them out of the piston for replacement.

An object of the present invention is to provide a piston which will obviate the difficulties above enumerated and one which will materially reduce the expense of repairs in that it will make it unnecessary to replace the entire piston, when wear takes place and reduces the efficiency of the piston.

The invention comprehends substantially a piston of composite design comprising a pair of piston elements which are held together by the piston rod nut so as to permit the piston to be easily taken apart to clean out any foreign matter which may lodge under the snap rings and make them inoperative, and for replacing the wide faced centering ring used in the piston construction, which ring takes up the wear and permits replacement in case of wear, at a relatively small expense.

With these objects in view, the invention consists in various features of construction and combination of parts, which will be first described in connection with the accompanying drawings, showing a pump piston of the preferred form embodying the invention, and the features forming the invention will be specifically pointed out in the claims.

In the drawings—

Figure 1 is a side elevation partly in section, of a displacement pump for pumping hot fluids, and illustrating the piston as used. Figure 2 is a longitudinal section through the piston with the piston rod removed.

Figure 3 is a cross-section on the line 3—3 of Figure 2.

Referring more particularly to the drawings, Figure 1 illustrates a displacement pump of any approved construction, such as used for the pumping of hot liquids, preferably hot petroleum oils, and this pump structure comprises essentially the pumping or fluid end A and the steam or power end B with the necessary connections C therebetween for operating the piston 1 of the pumping or fluid end A.

The piston 1 reciprocates within the cylinder lining 2 mounted in the bore 3 of the cylinder 4 and it is connected to the steam or power end B by the piston rod 5. A suitable stuffing box 6 of any approved construction is shown at the end of the cylinder 4.

The present invention relates wholly to the piston structure and as shown in Figure 2 of the drawings, the piston is of composite design comprising the two piston elements 10 and 11 which are substantially of the same size and shape.

To make it unnecessary to replace the entire piston when wear takes place during the operation of the piston, a wide face centering ring 12 is provided and this centering ring 12 fits in annular recesses 13 and 14 formed in the elements 10 and 11 at their inner facing ends to form a groove. The ring 12 overlaps the joint between the meeting ends of the elements and the shoulders 15 formed by the recesses 13 and 14 and is clamped in tight engagement with the edges of the centering ring 12 by the piston rod nut 16 which is threaded on the end of the piston rod 5 and clamps against the flat surface 17 on the piston element 11. The piston rod receiving bore 18 of the piston element 10 is tapered as clearly shown in Figure 2 of the drawings to facilitate the wedging action and firm clamping of the piston elements 10 and 11, centering ring 12 and piston rod 5 in a compact unit. The piston elements 10 and 11 are provided with annular recesses 19 and 20 and form grooves with the centering ring on one side, which receive eccentric snap rings 21 which are relatively stiff and strongly expansive to hold them against the inner surface of the cylinder lining 2. As the area of the ring in contact with the cylinder lining is large, the contact pressure per unit area is low enough for the wear of the cylinder lining

and of the ring to be small. It has also been found that the wide snap rings do not stick as do narrow snap rings. The snap rings 21 are held against rotation on the respective piston elements by lugs 22 formed on the rings which fit in suitable recesses 23 formed in the piston elements.

To facilitate the taking apart of the piston structure either for cleaning out any foreign matter which may lodge under the snap rings, or to permit replacing of the centering ring, jack bolt holes 24 are provided in the piston element or follower 11 and these openings extend from the flat face 17 through the element or follower 11 to its inner surface. The element or follower 11 is a slightly loose fit on the piston rod 5 so that by taking off the piston rod nut 16, which is castellated, eye bolts can be screwed into the jack bolt openings 24, for use in pulling the element 11 off the piston rod, or if the parts of the piston are carbonized together, the eye bolts may be screwed through the openings 24 and against the piston element 10 so that they act as jacks to force the elements 10 and 11 apart.

Jack bolt holes 25 are also provided in the centering ring 12 to facilitate the separating of the centering ring from the element or head 10, and the ring is further provided with an annular groove or cut-out 26 in its inside face which makes it possible to get a pinch bar in at this point to force the centering ring 12 off the piston head or element, if required.

As clearly shown in Figure 2 of the drawings, the jack bolt holes 24 are covered with the piston rod nut 16 which will prevent any tendency of the openings to fill with hot oil and then carbonize, and the openings 25 are closed by shoulder 14, with the same result.

From the foregoing description taken in connection with the accompanying drawings, it will be apparent that a piston construction

has been provided which will make it unnecessary to replace the entire piston when wear takes place in that the centering ring 12 may be replaced at a small expense and will then permit a piston considerably reduced in diameter to be successfully and effectively used.

It will be understood that the invention is not to be limited to the specific construction or arrangement of parts shown but that these may be modified widely within the invention defined by the claims.

What is claimed is:

1. A pump piston of composite construction comprising a pair of elements provided with annular recesses in their perimeters on their adjacent ends to form a groove, a centering ring in said groove overlapping the joint between the elements, each of said elements provided with an eccentric, annular groove adjacent the annular recesses therein, said grooves disposed whereby the shallowest portion of one groove will be opposed to the deepest portion of the other groove, and snap rings in said eccentric grooves.

2. A pump piston of composite construction comprising a pair of elements provided with annular recesses in their perimeters on their adjacent ends to form a groove, a centering ring in said groove overlapping the joint between the elements, each of said elements provided with an eccentric, annular groove adjacent the annular recesses therein, said grooves disposed whereby the shallowest portion of one groove will be opposed to the deepest portion of the other groove, and snap rings in said eccentric grooves, said centering ring provided with an annular groove in its inner face spanning the joint between the elements.

In testimony whereof I affix my signature.

WALTER C. GAGE.
